US00D956684S

(12) **United States Design Patent** (10) **Patent No.:** **US D956,684 S**
(45) **Date of Patent:** **** Jul. 5, 2022**

(54) **POWER SUPPLY**

(71) Applicant: **Shenzhen TIG Technology Co., Ltd,** Shenzhen (CN)

(72) Inventors: **Lulu Peng**, Shenzhen (CN); **Junfeng Zhang**, Shenzhen (CN)

(73) Assignee: **SHENZHEN TIG TECHNOLOGY CO., LTD**, Shenzhen (CN)

(**) Term: **15 Years**

(21) Appl. No.: **29/752,554**

(22) Filed: **Sep. 28, 2020**

(30) **Foreign Application Priority Data**

Aug. 13, 2020 (CN) 202030459597.2

(51) LOC (13) Cl. **13-02**

(52) U.S. Cl.

USPC **D13/103**

(58) **Field of Classification Search**

USPC D13/103, 107, 108, 110, 118, 119;
D14/432, 433, 434, 439

CPC H02J 7/342; H02J 7/0044; H02J 7/0045;
F02N 11/12

See application file for complete search history.

(57) **CLAIM**

The ornamental design for a power supply, as shown and described.

DESCRIPTION

The patent or application file contains at least one drawing executed in color. Copies of this patent or patent application publication with color drawings will be provided by the Office upon request and payment of the necessary fee.

FIG. 1 is a top, front, right side perspective view of a power supply, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

1 Claim, 7 Drawing Sheets
(7 of 7 Drawing Sheet(s) Filed in Color)
